US00D650476S

(12) **United States Design Patent**
Pecherer

(10) **Patent No.:** **US D650,476 S**
(45) **Date of Patent:** **** Dec. 13, 2011**

(54) **HAND OPERATED ARTICULATED INTUBATION STYLET**

(75) Inventor: **Eugen Pecherer**, Netanya (IL)

(73) Assignee: **Truphatek International Ltd.**, Netanya (IL)

(**) Term: **14 Years**

(21) Appl. No.: **29/371,617**

(22) Filed: **May 25, 2011**

(51) **LOC (9) Cl.** **24-02**

(52) **U.S. Cl.** **D24/112**

(58) **Field of Classification Search** D24/112-114, D24/133, 186, 130, 127; 606/181, 185; 604/164.01-164.09, 533, 232, 187, 168.01, 604/192, 19, 48, 93.01, 523, 524, 526, 174, 604/528; 600/185-188, 101, 139, 143; 128/200.26, 128/200.24, 207.14, 207.15

See application file for complete search history.

(57) **CLAIM**

The ornamental design for a hand operated articulated intubation stylet, substantially as shown and described.

DESCRIPTION

FIG. 1 is a front perspective view of a hand operated articulated intubation stylet;

FIG. 2 is a front elevation view thereof;

FIG. 3 is a left side elevation view thereof;

FIG. 4 is a rear elevation view thereof;

FIG. 5 is right side elevation view thereof;

FIG. 6 is a top plan view thereof; and,

FIG. 7 is a bottom plan view thereof

The features shown in broken lines depict environmental subject matter only and form no part of the claimed design.
